UNITED STATES PATENT OFFICE.

GEORGE H. ANDERSON, OF KALAMAZOO, MICHIGAN.

AUTOMATIC VALVE MEANS.

Application filed July 5, 1921. Serial No. 482,478.

To all whom it may concern:

Be it known that I, GEORGE H. ANDERSON, a citizen of the United States, residing at Kalamazoo, county of Kalamazoo, State 5 of Michigan, have invented certain new and useful Improvements in Automatic Valve Means, of which the following is a specification.

This invention relates to improved automatic valve means for regulating the water supply and maintaining the water level in a boiler and controlling an auxiliary supply for that purpose.

The objects of this invention are to provide an improved float valve means for the purpose of controlling the water supply and auxiliary water supply in a boiler. Objects relating to details and economies of construction and operation will definitely appear from the detailed description to follow. The objects are accomplished by the devices and means described in the following specification. The invention is clearly defined and pointed out in the claims.

A structure which is a preferred embodiment of my invention is clearly illustrated in the accompanying drawings forming a part of this specification in which:

Fig. I is a detail diagrammatic view of the structure in its relations to a steam boiler, a fragment only of which is shown.

Fig. II is an enlarged longitudinal sectional view through the valve structure including part of the steam chamber taken on a line corresponding to line 2—2 of Figs. III and IV.

Fig. III is a diagrammatic sectional view on a line corresponding to line 3—3 in Figs. I and II the valve being in full lines.

Fig. IV is an enlarged detail sectional view through the valve proper taken on the line 3—3 of Figs. I and II.

In the drawings the sectional views are taken looking in the direction of the little arrows at the ends of the section lines and similar numerals of reference refer to similar parts throughout the several views.

Considering the numbered parts of the drawings by their numerals, 1 is a steam boiler, a fragment only of which is shown.

2 is the outer casing of the steam chamber for my improved valve structure the same being provided with a steam tight flanged cover 3. 4 is the pipe connection from the upper part of the steam chamber to the 55 steam space of the boiler.

5 is the flanged pipe connection from the casing 2 to the boiler below the water line. By this arrangement the water level within the casing 2 is maintained at the water level 60 of the boiler.

6 is the water supply pipe extending through the stuffing box 7 in the end of casing 2 and connecting at its inner end to the valve casing 8 which is disposed and 65 arranged within the said chamber 2. The same is provided with a detachable cover 8'. 9 is the outer chamber of the valve and 10 is the inner chamber formed by casing 10'. An auxiliary central chamber 11 70 formed by casing 11' is also provided, the chamber 10 being connected to the boiler through the pipe 12 which is arranged to extend through the flanged pipe 5 well into the boiler.

Vertically disposed through the bores 16 of the inner casing 10' and the bore 17 of the central casing 11' of auxiliary chamber 11 is the balanced piston valve 13. This is provided with lateral port openings 14—14 80 towards its upper and lower ends adapted to open and connect the outer valve chamber 9 to the inner valve chamber 10.

A reduced portion 15 forms a port through the bores 17 to connect the auxiliary chamber 11 to the inner chamber 10. (See Figs. II and IV.)

In the up position the valve is completely closed. When it is lowered slightly through the bores 16 the outer valve chamber 9 connects with the inner valve chamber 10 and delivers water from the pipe 6 through the valve, through the pipe 12 into the boiler. When it is lowered a little farther the auxiliary chamber 11 is also connected to deliver water from the auxiliary source through the pipe 12 into the boiler. The chamber 11 is connected by pipe 11'' to a city water main or other auxiliary source of supply. (See Figs. I and III). The 100

2
 valve 13 is provided with an upwardly extending stem 18 and the float lever 20 is connected thereto by a pivot 19, the end of said lever 20 being fulcrumed at 21 at the upper end of the link 22 which is pivoted at 23 to the detachable top 8' of the valve chamber. The float lever 20 is provided with a float 24 for controlling the same.

From this arrangement it will be seen that the valve structure controls the supply of water delivered to the boiler. This is ordinarily supplied by a pump through pipe 6, the pipe having, of course, a suitable check valve.

When the water level of the boiler descends the float drops, opening the valve and permitting the supply from the pump to deliver through pipe 6 through the valve from chamber 9 through chamber 10 through pipe 12 into the boiler. If the pump fails to act for any reason or the supply from the main source fails, of course, the water level will continue to lower. A farther drop of valve 13 permits the water from the auxiliary source to enter through pipe 11" to chamber 11 through port 17 to the central chamber, thus supplying and protecting the boiler.

Having thus described my invention what I claim as new and desire to secure by Letters Patent is:

1. In a control valve structure, the combination of the casing connected by suitable pipes at the upper portion to the steam space and at the lower portion to the water space of a boiler, a supply pipe leading into the said casing and a delivery pipe leading therefrom within the connecting pipe to the water space of the boiler, a valve the casing of which comprises an outer chamber connected to said supply pipe and an inner chamber connected to said delivery pipe, a central auxiliary chamber, an auxiliary supply connected to said central auxiliary chamber, a vertically disposed piston valve through bores on the opposite sides of the said inner chamber and alined bores in the walls of said central auxiliary chamber, the said valve being provided with ports timed to open successively to the inner chamber and to the central auxiliary chamber, a piston rod extending upwardly therefrom, a lever fulcrumed on a suitable link to the upper portion of said valve casing pivotally connected to said stem, a float carried by said lever coacting for the purpose specified.

2. In a control valve structure, the combination of the casing connected by suitable pipes at the upper portion to the steam space and at the lower portion to the water space of a boiler, a supply pipe leading into the said casing and a delivery pipe leading therefrom within the connecting pipe to the water space of the boiler, a valve the casing

of which comprises an outer chamber and 65 an inner chamber, a central auxiliary chamber, an auxiliary supply connected to said central auxiliary chamber, a vertically disposed piston valve through bores on the opposite sides of the said inner chamber and 70 alined bores in the walls of said central auxiliary chamber, the said valve being provided with ports timed to open successively to the inner chamber and the central auxiliary chamber, a float and connection within 75 the said casing to control the said valve.

3. In a control valve structure, the combination of the casing connected by suitable pipes at the upper portion to the steam space and at the lower portion to the water space of a boiler, a supply pipe leading into the said casing and a delivery pipe leading therefrom within the connecting pipe to the water space of the boiler, a valve the casing of which comprises an outer chamber, and 80 an inner chamber, a central auxiliary chamber, an auxiliary supply connected to said central auxiliary chamber, a piston valve disposed through bores on the opposite sides of the said inner chamber and alined bores 85 in the walls of said central auxiliary chamber, the said valve being provided with ports timed to open successively to the inner chamber and the central auxiliary chamber, a float and connection within 90 the said casing to control the said valve.

4. A control valve structure having an outer casing connected to both the steam and water space of a boiler, a water connection disposed through the said casing for delivering water to the boiler, an auxiliary water connection leading into the said outer casing with valve controlled connection to the water delivery, a balanced piston valve, said valve being provided with ports timed to connect the main water delivery and the auxiliary supply successively, a float and connection within the said chamber to actuate and control the said valve.

5. A control valve structure having an outer casing connected to both the steam and water space of a boiler, a water connection disposed through the said casing for delivering water to the boiler, an auxiliary water connection leading into the said outer casing with valve controlled connection to the water delivery, a float valve means timed for controlling the main supply and the auxiliary supply successively for controlling said delivery.

6. In a control valve structure a valve comprising an outer casing and an inner casing forming an inner chamber, a central auxiliary chamber formed by a central valve casing, a balanced piston valve disposed through alined bores in the opposite walls of said central valve casing and automatic means to control said valve, the said valve

being provided with ports timed to open successively to the inner chamber and the central auxiliary chamber.

7. In a control valve structure a valve comprising an outer casing and an inner casing forming an inner chamber, a central auxiliary chamber formed by a central valve casing, a balanced piston valve disposed

through aligned bores in the opposite walls of said central valve casing, the said valve being provided with ports timed to open successively to the inner chamber and the central auxiliary chamber.

In witness whereof, I have hereunto set my hand and seal.

GEORGE H. ANDERSON. [L.S.]
